UNITED STATES PATENT OFFICE.

GEORGE D. McLAUGHLIN, OF CHICAGO, ILLINOIS.

DESIGN FOR A CASING OR CARTON.

41,098.

Specification for Design.

Patented Jan. 17, 1911.

Application filed November 5, 1909. Serial No. 526,478. Term of patent 7 years.

To all whom it may concern:

Be it known that I, GEORGE D. McLAUGHLIN, a citizen of the United States, residing at Chicago, in the county of Cook and State of Illinois, have invented a new, original, and ornamental Design for Casings or Cartons, of which the following is a specification, reference being had therein to the accompanying drawing, forming part thereof.

In the drawing Figure 1 is a front view of a carton or casing showing my new design, and Fig. 2 is a rear view of the carton or casing of Fig. 1.

The leading feature of my design consists in a casing or carton for food products such as coffee, which comprises a rectangu-

lar body portion composed of front, rear and side walls and ends, and having ornamental figures or symbols on its surface, and an ornamental strip or band disposed near its center.

The reference letter *a* indicates the body of the carton or casing, the letter *b* its ornamental figures or symbols, and the letter *c* an ornamental band or strip.

I claim:

The ornamental design for a casing or carton, as shown and described.

GEORGE D. McLAUGHLIN.
